CLAIM

(52) **U.S. Cl.** D14/258

The ornamental design for a combined digital disc player and automotive navigation system, as shown and described.

(58) **Field of Classification Search** D10/65,

DESCRIPTION

D10/80; D12/192; D14/496, 157, 257–258,
D14/299, 217, 126, 132; 455/344–351; 369/75.11,
369/75.21, 77.11, 77.21; 720/612, 619, 647,
720/655

See application file for complete search history.
